PHOTOGRAPHIC PLATE HOLDER

Samuel S. Levin, Fox Chapel Borough, Pa.

Application May 24, 1938, Serial No. 209,687

8 Claims. (Cl. 95—66)

This invention relates to photography and more particularly to holders in which light-sensitive, cut films may be exposed in a camera.

Holders of the general nature of my present invention have been somewhat unsatisfactory. They are commonly manufactured from wood or from wood faced or reinforced with metal, but both types have a relatively short effective life in that they are easily broken, they warp out of shape and are affected by weather conditions, drying out in dry climates and swelling in humid climates. In some few cases these holders have been made from sheet metal, but these have never been satisfactory even though they are resistant to climatic changes.

In many prior art holders no effective means is provided for inserting and removing the cut film conveniently and easily without damage to such film. In many cases it has been necessary to bend or distort the film in order to insert it in the holder. In at least one instance the holder has been provided with one or more hinged sections to facilitate insertion and removal of the cut film, but these have been of weak or inadequate construction insofar as the hinge is concerned, and thus have not solved satisfactorily the problem of producing a good film holder having the desired qualities and characteristics.

One of the objects of my present invention is to produce a strong and rigid but light and inexpensive film holder which has new and useful characteristics not shared by prior film holders.

Another object is to produce a film holder wherein the frame is provided with hinged portions and wherein the hinges are as strong and durable as any other part of the holder.

A further object is to produce a holder having dark slides of such nature that the photographer will always know whether a given film has been exposed or not and wherein the dark slides are each formed from a single piece of non-metallic material.

A still further object of the invention resides in the provision of a photographic film holder, the frame of which is composed of extruded metal, which can be sold at the same cost as wooden holders.

Other and further objects and advantages will be understood by those skilled in this art or will be apparent or pointed out hereinafter.

In the accompanying drawing wherein I have illustrated film holders embodying my present invention and wherein like numerals designate corresponding parts in the various views:

Figure 1 is a side elevational view of my new

film holder with portions thereof broken away to disclose parts of the underlying construction;

Fig. 2 is a view generally similar to Fig. 1 but wherein the dark slide nearest the observer has been removed to show how film is inserted in and removed from the holder;

Fig. 3 is a vertical sectional view taken on line III—III of Fig. 1;

Fig. 4 is a transverse sectional view taken on line IV—IV of Fig. 1;

Fig. 5 is a fragmentary sectional view on an enlarged scale illustrating a modified form of hinge;

Fig. 6 is a view similar to Fig. 5 of a further modified form of hinge; and

Fig. 7 is a view similar to Figs. 5 and 6 of another form of hinge forming a part of my present invention.

The holder of my invention has a metal frame 10 of generally rectangular configuration and composed of extruded metal. These extruded metal parts may be made in any suitable manner and in any suitable number of pieces which are subsequently secured together in proper permanent relationship by soldering, welding, by the use of screws, or in any other known or desired manner.

As will be noted from Fig. 4 in particular, the extruded metal framework is provided with a relatively large exterior peripheral groove 11 and with lateral or side grooves 12, thus minimizing the amount of metal necessary to produce the holder, reducing the cost thereof and, at the same time, resulting in the production of a holder which is light in weight without sacrificing strength, rigidity, or durability.

The frame 10 is provided on its inner periphery with a plurality of spaced slots, three of which are shown in the drawing. There is a central slot 13 in which is disposed a metal partition plate 14 which divides the holder centrally into two parts. As will be understood from Fig. 3, the lower end of partition plate 14 rests in the tongue or spacer 15 slotted at 16 for such purpose and the upper end of the partition plate rests in the body 17 at 18 the upper part of the frame. On either side of the central slot 13 are the two slots numbered 18 and 19. These slots extend into the hinged sections designated as a whole at 20 at the bottom of the holder and along body portion 17 at the top 21 of the holder and are adapted for the insertion and removal of dark slides 21 which are preferably composed of hard rubber, molded to shape. These dark slides are each made in one piece contrary to prior practice in this connection.

These dark slides 21 are each made in a single piece, as stated, and each is provided with an enlarged head portion 22 along one lateral surface of which a groove 23 is formed. These dark slides 21 pass through the slots 18, 19 and form a pair of compartments 24, one on either side of partition plate 14, and it is these compartments into which cut film is inserted and from which the same is removed, it being understood, of course, that the film inserting and removing operations take place in a dark room.

To prevent access of light to the film-receiving compartments 24, light-sealing means is provided in the upper portion of the frame 10 of the holder. For this purpose, I recess or cut away the metal of the portion 17 as indicated by the numeral 25 in Fig. 3. In these two formed recesses a light excluding material is positioned such as velour, velvet, or other suitable fabric, particularly a so-called pile fabric, and such is indicated by the numeral 26. Portions 27 of the frame 10 likewise have recesses in which pile fabric is located as will be understood from the use of the same numerals 25 and 26 thereon.

As already stated, the enlarged head portions 22 of dark slides 21 are each provided with a single lateral groove 23. Each such groove may be marked in a distinguishing manner such as by painting or staining it or a strip of contrasting material may be placed in each such groove. I may also use a phosphorescent material in each groove such as a radium paint. The paint, being below the surface of the head 22, is protected against wear, chipping off, and the like. The dark slides are positioned in the holder in such manner that when the film 28 within the compartments 24 is unexposed the grooves face outwardly. By seeing the contrasting mark the photographer will immediately know that the film in that particular compartment is unexposed and is ready for exposure. Since it is necessary to remove each dark slide when it is desired to expose the film in a camera, the photographer will replace the slide in the reverse manner with the groove facing inwardly. Thus he will, at a glance, know that when the groove or mark is not visible the film has been exposed, thus avoiding danger of double exposure and of wasted film.

Means is provided for holding the dark slides in place and this means may take the form of a suitable latch designated by the numeral 29, a latch being provided for each slide. These latches have a horizontal portion resting on top 55 of the head of each slide so that when it is desired to remove a slide it is only necessary to turn the latch so as to disengage the horizontal portion from the head 22. This prevents accidental and undesired movement of the dark slides 60 and thus avoids inadvertent exposure or re-exposure of film. As shown, these latches have enlarged portions 30 disposed in under-cut recesses 31 formed in the top of the metal frame portion 17. While I have illustrated a simple and 65 effective form of latch it is to be understood that I am not restricted to the particular latch referred to as other forms may be used equally well provided they meet the conditions involved. The recesses 31 may either communicate with a 70 similarly shaped slot or the material around the recess may be sprung somewhat and then crimped to allow insertion of the latches.

As shown best in Figs. 2 and 3, the sides of the metal frame 10 are provided with relatively thin 75 ribs 31 which project inwardly a short distance

from the frame and which are sufficiently spaced from central partition 14 to permit film to be received thereunder. These ribs 31 extend from the under surface of the top portion 17 of the frame to a point short of the transverse bottom portion 32 of such frame and the lower end of each such rib 31 is beveled or rounded as shown at 33 so as to guide film into proper position without damaging such film. In Fig. 2 the cut film 28 is shown which has been nearly fully 10 inserted, thus clearly illustrating the manner of inserting and removing film.

In order to insert and remove film without unduly bending, distorting, or otherwise damaging the film, I provide the lower transverse frame portion 32 with the hinged sections specifically marked 32'. Each such hinged section has the slot 19 above referred to for receiving the lower end of the dark slide 21 and, in general, is complementary to the tongue portion 15 which has a 20 more or less T-shaped configuration as shown in Fig. 3. In the form shown in Fig. 3, each hinged section is provided with a recess 34 which receives the adjacent portion 35 of the generally T-shaped tongue portion 15. Below such recess 25 the hinged section has a thin cross-section and abuts the shank of the tongue. Below such, each hinged section flares outwardly to produce a transversely extending rod-like extremity 36 which fits into a circular transversely extending 30 channel 37 formed in the frame portion 32 in such manner that each hinged section can be partially swung hinge fashion into the dotted line position shown in Fig. 3 without causing disengagement of the parts which are thus permanently associated since the diameter of each rod-like portion is greater than the effective opening of the said circular groove.

Thus, in utilizing a film holder such as I have described, either dark slide, after being unlatched, is withdrawn from the holder, the appropriate hinged section is swung outwardly as far as it will go, film is inserted or removed, and then the dark slide repositioned, care being taken as above pointed out to have the groove 45 23 of each dark slide in the appropriate position depending upon whether film has been exposed or not. When each dark slide is in place the hinged section receiving it is locked in position. Conversely, removal of the dark slide unlocks the hinge section and enables it to be 50 opened.

In Figs. 5, 6, and 7 I have illustrated modifications of the hinged sections and in these modifications it will be noted that it is possible to 55 swing the hinge sections outwardly somewhat further than in connection with Fig. 3. While in the form shown in Fig. 3, the hinged sections can ordinarily be swung through an arc of at least about 60°, in Figs. 5, 6, and 7 the modified 60 hinge sections are capable of being swung through an arc of about 90-110°, thus expediting the insertion and removal of film to a corresponding extent and presenting structural advantages as will be understood.

In Fig. 5 the central or tongue-like portion 15a of the frame has the configuration therein illustrated which is characterized by having external shoulders 15a' and a slot 16a for the reception of a partition plate as above referred to. 70 The hinged sections 32a are shaped so as to interfit with the shoulders 15a' and are provided with the slots 18a, 19a for the reception of the dark slides. The rod-like extremities 36a of the hinged sections lie and operate within the re- 75

cesses or spaces 31a which extend across the bottom portion of the frame as will be understood from what has been explained above. The ends of 36a extend into the frame beyond member 32. 5

5 Hinges 36b are secured to members 32a as shown.

In Fig. 6 the tongue-like portion 15b tapers upwardly and in the narrowest portion thereof a slot 16b is provided for the reception of the central partition plate as before. In the under- 10 side of tongue-like portion 15b, transversely extending circular grooves 37b are provided which are adapted to receive the rod-like extremities 36b of the hinged sections 32b, movement of the hinged sections being limited by the abutting of 15 the faces 32b' of the hinged sections with the faces 15b' of the tongue-like portion. As before, each hinged section is provided with a slot 19a, 19b for reception of the lower end of a dark slide. 20

In Fig. 7 the hinged sections 32c are provided with hook-shaped extremities 32c' which are adapted to operate in correspondingly shaped passageways 37c formed in the tongue-like portion 15c. Each hinged section has a dark slide receiving slot 18c, 19c and the tongue section 25 itself has a partition plate receiving slot 16c. It will be noted that the tongue-like portion has a bulbous extremity 15c' and that the hinged sections 32c have complementarily shaped recessed portions 32c'' adapted to receive the extremity of the tongue-like portion. 30

The foregoing is presented as illustrative rather than limitative and it is to be understood that within the purview of my invention I may resort to various alterations, modifications, additions, or omissions without departing from the spirit and principle hereof. Rather the invention is to be defined by the appended claims. While I have referred to extruded metal as being the material of which the frame or holder is formed, 40 I prefer to use aluminum. Other light metals may be used where they meet the conditions involved.

While I have described my holder as made up of a number of extruded aluminum pieces permanently secured together as by welding, soldering, and the like, I prefer to connect portions 27 to the holder by screws, bolts, or the like (not shown) so that the light-sealing material may be replaced when necessary. The use of such fastening instrumentalities has been indicated on the drawing by the numerals 38.

Having thus described my invention, what I claim is new and desire to secure by Letters Patent is:

55 1. A photographic film holder comprising a rectangular extruded aluminum frame and integral hinge provided with spaced grooves in their inner peripheries, a partition plate fixed in one of said grooves dividing the frame into two compartments, a dark slide in each of the other grooves projecting beyond said holder and normally closing each such compartment, each dark slide being slidable in and out of said holder and each having an enlarged head portion with a 60 transverse groove therein on one side, means for normally preventing movement of said dark

slides, means on said frame adjacent the dark slide grooves for holding cut film in position for exposure, means for light-sealing the said compartments and means for enabling film to be inserted in and removed from each compartment, 5 said last means having slots to receive the ends of the dark slides for locking the same in closed position when said dark slides are engaged in said slots.

2. A photographic film holder as set forth in 10 claim 1 wherein the last-named means has a relatively stationary central portion and swingable hinge-like outer portions having rod-and-groove connections with said central portion.

3. In a photographic film holder, an extruded, 15 rectangular aluminum frame characterized by lightness, strength and resistance to warping, said frame being composed of a number of individual extruded pieces integrally secured together in permanent relationship. 20

4. In a photographic film holder, a bottom extruded metal frame piece composed of a central tongue-like portion and a hinged section on each side thereof, the hinged sections being substantially complementary to the tongue-like section 25 and being hingedly connected thereto throughout their transverse extent.

5. In a photographic film holder, a bottom extruded metal frame piece composed of a central stationary portion and a hinged-section on each 30 side thereof, the hinged sections being substantially complementary to the central portion and being provided with transverse terminal enlargements adapted to fit into and to have hinged action with corresponding recesses in said central 35 portions.

6. A photographic film holder as set forth in 40 claim 5 wherein the central portion consists of a tapering tongue-like piece having shoulders against which the hinged sections abut when the hinged sections are swung through an arc of about 90°.

7. A photographic film holder as set forth in 45 claim 5 wherein the central portion is an upwardly tapering tongue-like piece with a slot in its upper extremity and wherein the tongue-like piece and hinged sections are provided with cooperating shoulders which abut when the hinged sections are swung open to their maximum extent. 50

8. In a photographic film holder, an extruded aluminum frame provided with an integral hinge of the same material, said hinge including a centrally disposed relatively stationary upwardly tapering tongue-like portion having a longitudinally extending slot in its narrowest portion and spaced circular grooves in its underside, and a pair of hinged sections one of which is disposed on each side of said tongue-like portion and each of which has a rod-like extremity receivable within the circular grooves aforesaid, the said tongue-like portion and hinged sections being structurally complementary and being provided with co-operating means to limit movement of said 60 hinged sections. 65

SAMUEL S. LEVIN.
